UNITED STATES PATENT OFFICE.

CARL E. BAUER, OF HAMMOND, INDIANA.

METHOD OF MAKING DRAW-BAR YOKES.

1,330,575.

Specification of Letters Patent. Patented Feb. 10, 1920.

Application filed October 21, 1918. Serial No. 259,065.

To all whom it may concern:

Be it known that I, CARL E. BAUER, a citizen of the United States, and resident of Hammond, in the county of Lake and State 5 of Indiana, have invented certain new and useful Improvements in Methods of Making Draw-Bar Yokes, of which the following is a specification.

My invention relates to draft rigging for 10 railway cars and particularly to a novel process of producing a yoke for use therein.

The object of my invention is to provide a process of producing a draft rigging yoke whereby such yokes may be cheaply and 15 expeditiously manufactured. The yoke which results from the process of my invention has many advantages over those heretofore proposed. It is desirable to provide a yoke head adapted to surround the draw bar butt 20 and to provide ears thereon by means of which the yoke may be attached to a draw bar by means of a key. However, the difficulty in the production of such yokes has been in the provision of suitable means of 25 attachment between the yoke arms and the head; this is because of the limited space within which the connection must be made and the limited quantity of material which may be employed for making the connection.

30 Preferably, the inner faces of the yoke arms should lie in close proximity to the draw bar butt when the parts are in their operative positions. First, for the reason that the pull exerted by the draw bar will be in a 35 more direct line with the arms, and, second, for the reason that when the forward ends of the arms are spaced away from the draw bar butt it implies an increase in the vertical depth of the device at that point and the 40 space at that point is limited.

The yoke produced as the result of my method avoids the difficulties heretofore encountered and as the steps and mechanism required for producing the yoke are few 45 and simple, it is desirable from many standpoints.

The yoke and the process of producing it, will be better understood by reference to the accompanying drawings in which—

50 Figure 1 is a longitudinal section view

through a yoke constructed in accordance with my invention;

Fig. 2 is a view showing the bar which I employ in forming the arms of the yoke;

Fig. 3 is an edge view thereof;

Fig. 4 is a view of the bar after the same has been shaped and before it is bent into its final form;

Fig. 5 is a view showing a blank from which the head is formed;

Fig. 6 is a perspective view of the head, after the first operation.

Fig. 7 is a diagrammatic illustration of a pair of dies adapted to form the band or head;

Fig. 8 is a similar view showing the dies for removing the end wall of the band;

Fig. 9 is a similar view showing the dies which may be employed for upsetting the bar at its middle portion;

Fig. 10 is an end view thereof; and

Fig. 11 is a view showing the dies employed for shaping the yoke.

In carrying out the process, the arms, comprising the U shaped portion of the 75 yoke, are formed by upsetting the bar 10 at its middle to form the thickened portion 11, this being done in a common bull-dozer or forging machine such as shown in Figs. 9 and 10. In these figures the bar 10 is shown as being clamped between upper and lower die members 10^a, 10^b, the lower member having a recess 10^c therein. Pressure being applied to the ends of the bar and the intermediate portion of the bar being heated, the 80 metal will be caused to flow into the recess 10^c. The ends of the bar are then shaped to provide the shoulders or abutments 12, this being done in an ordinary forging machine not shown, after which the part is 85 bent into its final form, the ends being straight as shown by the dotted lines lettered 13 in Fig. 1.

A device in which the yoke may be bent into U-shape is shown in Fig. 11, in which 95 the bottom die member 10^d is provided with a recess and a plunger 10^e is employed for forcing the bar into the full line position of Fig. 11.

The head is preferably formed by first 100

cutting a billet or slab of the proper length to provide the requisite amount of material after which the block of metal, as shown in Fig. 5 is heated to a welding temperature and placed in suitable shaping dies 15^a, 15^b, 5 actuated by a powerful press not shown, wherein a rectangular hollow member is formed as shown in Fig. 6. The end wall 15 is then punched out leaving as shown in 10 Fig. 1 a rectangular band comprising the side walls 16, the top and bottom walls 17, and the slotted ears 14 which are formed as extensions of the side walls 16. The punching press may comprise the punch 15^c 15 and the apertured punch plate 15^d on which the incompletely formed head is placed in order that the end wall 15 may be punched out. The U shaped member of the yoke is then assembled with the head, with the forward ends of the arms in the dotted line 20 position of Fig. 1, whereupon the said ends are bent backwardly to materially overlie the top and bottom walls 17 of the head. The bending is done while the forward ends 25 of the arms are highly heated and the head is cold, and the parts are tightly fitted while in that condition. Upon cooling the arms will be shrunk on the head and still more tightly engage the same. As an added assurance of security I may join the parts by 30 spot welding as indicated at 19 in Fig. 1. This welding may readily be accomplished after the parts are finally assembled and serves to firmly unite the same without 35 weakening.

Preferably the ears 14 are formed in the first operation by the action of the shaping die, after which the slots 14^a may be punched or drilled. However, the shaping of the 40 ears may be accomplished subsequently if desired, it being understood that sufficient metal will be allowed to project from the side walls for that purpose.

One of the great advantages in the manufacture of a head according to the process 45 described is in the fact that it is substantially entirely completed in the two operations. After the head and arms are assembled in the described manner the yoke is, 50 for all practical purposes, an integral structure and is much lighter than a cast yoke having the same strength.

A yoke formed in the manner described 55 may be constructed very cheaply, in fact much more cheaply than a cast yoke. It will be seen that parts are joined without the use of rivets or any fastening devices which necessitate perforating, and thereby weakening the different parts.

60 I claim:

1. The method of making a draw bar yoke, 65 which consists in applying pressure centrally of a flat slab while at a welding temperature by means of a die thereby pressing

the same into cup-shape, then removing the bottom wall of the cup thereby forming a 70 seamless band, then applying pressure to a bar to upset an intermediate portion thereof, then bending the bar into U-shape and causing the free ends to enter the band, then bending back the free ends of the arms over the band while said ends are heated, shoulders being provided on the arms adapted to engage the side of the band opposite to the overturned ends of the arms, then allowing 75 the parts to cool whereby the ends of the arms are shrunk onto the band, substantially as described.

2. The method of making a draw bar yoke, 80 which consists in applying pressure centrally of a flat slab while at a welding temperature by means of a die thereby pressing the same into cup-shape, then removing the bottom wall of the cup thereby forming a 85 seamless band, then applying pressure to a bar to upset an intermediate portion thereof, then bending the bar into U-shape and causing the free ends to enter the band, then bending back the free ends of the arms over the band while said ends are heated, shoulders being provided on the arms adapted to engage the side of the band opposite to the overturned ends of the arms, then allowing 90 the parts to cool whereby the ends of the arms are shrunk onto the band, then electrically 95 welding the band to the ends of the arms, substantially as described.

3. The method of making a draw bar yoke, 100 which consists in applying pressure centrally of a flat slab while at a welding temperature by means of a die thereby pressing the same into cup-shape, then removing the bottom wall of the cup thereby forming a 105 seamless band, then applying pressure to a bar to upset an intermediate portion thereof, then bending the bar into U-shape and causing the free ends to enter the band, then bending back the free ends of the arms over the band, then permitting the arms to shrink 110 into tight engagement with the band, substantially as described.

4. The method of making a draw bar yoke, 115 which consists in applying pressure centrally of a flat slab while at a welding temperature by means of a die thereby pressing the same into cup-shape, then removing the bottom wall of the cup thereby forming a 120 seamless band, then applying pressure to a bar to upset an intermediate portion thereof, then bending the bar into U-shape and causing the free ends to enter the band, then bending back the free ends of the arms over the band, then electrically welding the band to the ends of the arms, substantially as described.

5. The method of making a draw bar yoke, 125 which consists in applying pressure centrally of a flat slab while at a welding tempera-

ture by means of a die thereby pressing the same into cup-shape, then removing the bottom wall of the cup thereby forming a seamless band, then bending a bar into U-shape and causing the free ends to enter the band, then bending back the extremities of the arms over the band while the said extremities are heated, then permitting the extremi-

ties of the arms to shrink into tight engagement with the band, substantially as de- 10 scribed.

Signed at Hammond, Ind., this 16th day of October, 1918.

CARL E. BAUER.
